[57] CLAIM

The ornamental design for stacking plastic buffet ware, as shown.

DESCRIPTION

FIG. 1 is a perspective view of a first embodiment of the stacking plastic buffet ware of the invention;

FIG. 2 is a top plan view thereof;

FIG. 3 is a bottom plan view thereof;

FIG. 4 is a first side elevational view thereof;

FIG. 5 is a front elevational view thereof;

FIG. 6 is a second side elevational view thereof;

FIG. 7 is a rear elevational view thereof;

FIG. 8 is a top plan view of an alternative embodiment of the invention;

FIG. 9 is a bottom plan view thereof;

FIG. 10 is a first side elevational view thereof;

FIG. 11 is a rear elevational view thereof;

FIG. 12 is a second side elevational view thereof; and,

FIG. 13 is a front elevational view thereof.
